(57) **CLAIM**

The ornamental design for a balloon arch stand, as shown and described.

DESCRIPTION

FIG. 1 is a front, right and top perspective view of a balloon arch stand, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1.

The dot-dash broken lines in FIGS. 1 and 8 depict the boundaries of the enlargements that form no part of the claimed design.

1 Claim, 8 Drawing Sheets(56)
